UNITED STATES PATENT OFFICE.

JAMES A. VANDIVIER, OF BARNSDALL, OKLAHOMA.

RAIL JOINT.

Application filed August 24, 1922. Serial No. 584,080.

To all whom it may concern:

Be it known that I, JAMES A. VANDIVIER, a citizen of the United States, residing at Barnsdall, in the county of Osage and State 5 of Oklahoma, have invented certain new and useful Improvements in Rail Joints, of which the following is a specification.

This invention has reference to an improved rail joint and provides means for 10 securely and firmly joining the ends of rail sections without the use of bolts or fish plates.

An essential object of the invention is to provide an interlocking joint for rail road 15 rails whereby the latter may be securely and firmly connected together through the length of the track and held against vertical or longitudinal creeping movement.

Various other objects and advantages of 20 the invention will become apparent from the following description.

In the drawing:

Figure 1 is a view in side elevation of the proposed rail-joint

25 Figure 2 is a top plan view thereof

Figure 3 is a transverse longitudinal section taken horizontally thru the joint as indicated on line 3—3 of Figure 1, and

30 Figure 4 is a view, in perspective, of two rail-joint units.

Describing the invention in detail A and B respectively designate rail sections having their adjacent ends constructed as shown to advantage in Figure 4 so as to interlock 35 with one another to provide the joint. The base of rail A is cut out adjacent one end to provide a T-shaped tongue 10 the head of which is narrower than the total width of the rail base. Tongue 10 engages in a cor- 40 respondingly shaped recess 11 provided in the adjacent end of rail B. The web 12 of each rail is thickened at the joint, as indicated at 13, and the thickened portion of rail B terminates in line of the inner wall of 45 recess 11 so as to provide a shoulder 14 on each side of the rail and beyond which the web extends, as indicated at 15. The tread of rail B is cut away to provide a T-shaped head 16 for the web extension 15 as may be 50 seen to advantage in Figure 4.

Rail A has its tread suitably recessed as at 17 to receive the key head of rail B while the thickened portion 13 of the rail is slotted, as at 18 to receive the web extension 15 of 55 rail B. It will thus be seen that the end of one rail is adapted to be interlockingly en-

gaged with the end of the adjacent rail, the T-heads of both rails serving to prevent their being pulled apart by longitudinal stresses.

Web portions 15 and 18 of rails A and B respectively are provided with openings 19 which are adapted to be in alignment when the two rails are joined together. These openings face laterally of the joints and are adapted to be penetrated by a key 20 as indicated in Figure 3. This key has a square shoulder 21 at one end and an opening in the other end for a wedge pin 22 which locks the key in position. This key passes thru the joint near the bottom of the rail and prevents the rails from moving up and down when the joint is locked.

In assembling the joint, rail B is first lined up with rail A and engaged with the latter by being first elevated a slight distance so as to bring recess 11 above tongue 10 and head 16 above recess 17. Rail B may then be moved forwardly until web portion 15 of rail B enters slot 18 of rail A, the side walls 80 of the slot passing in recess 11 and engaging with shoulders 14. The lowering of rail B will then cause tongues 10 and 16 to respectively enter the recesses provided to receive them, the locking key being then inserted 85 thru the joint after the rails are properly positioned with respect to one another.

It is not intended that the invention be limited to the precise detail of construction illustrated in the accompanying drawing 90 and herein described since it is obvious that various modifications and variations may be resorted to in connection with the structural features of the joint. And while the drawing illustrates but one end of each rail it is 95 to be understood that both ends of the same rail are to be so equipped as to be usable in a joint of the character herein disclosed.

From the foregoing it is believed that the advantages and novel features of the invention can be readily understood and that further detail description is unnecessary.

What is claimed is:

A rail joint comprising a rail section having the base cut out adjacent one end to provide a T-shaped tongue the head of which is narrower than the total width of the rail base and having a central portion of the tread and web cut away vertically above the T-shaped tongue to provide a narrow recess in the web and a T-shaped slot in the tread positioned reversely with respect to

the T-shaped tongue of the base, a second rail section having its base provided with an open recess to receive the said T-shaped tongue of the other rail section and shaped to correspond to the said tongue, said second rail section having its web and tread also cut away to provide a narrow web portion engageable in the recess of the web of the other rail section and a T-shaped tongue on 10 the tread for engaging in the T-shaped slot of the said other rail section; the said nar-

row web portion of the second rail section having its lower edge spaced upwardly from the open recess in the base sufficiently to permit passage therebetween of the T-shaped tongue of the said other rail section; and locking means including a key adapted to be inserted transversely thru aligned openings in the interfitting portions of the webs of the rail sections. 15

In testimony whereof I affix my signature. 20
JAMES A. VANDIVIER.
